DISPENSING DEVICE

Joseph T. Bell and Charles E. Seacrist, Alliance,
Ohio

Application March 13, 1941, Serial No. 383,141

4 Claims. (Cl. 221—147)

This invention relates to a dispenser for catsup and the like and is an improvement on the construction disclosed in the Karcher Patent No. 2,024,005 granted December 10, 1935.

The principal object of the invention is to provide a dispenser of the general type shown in the Karcher patent but which is more satisfactory in operation.

More particularly it is the aim of the invention to improve the construction and operation of the ejecting means including the means for guiding the ejector proper so as to better direct the catsup or other material being dispensed to the inner end of the delivery spout.

In its more specific aspects, the invention aims also to provide an ejecting mechanism including a part which has an agitating action on the catsup or other material in the receptacle to which my improved mechanism is applied.

In still another aspect the invention aims to improve the upper end of the receptacle, to provide for better delivery of the material from the discharge spout with less likelihood of drippage, and to facilitate the operation of the ejecting mechanism and to improve the appearance of the device so that it will be neat and attractive and serve as an ornamental as well as a useful device on a table.

The invention may be further briefly summarized as consisting in certain novel details of construction and combinations and arrangements of parts which will be described in the specification and set forth in the appended claims.

In the accompanying sheet of drawings illustrating the preferred form of the invention,

Fig. 1 is a vertical sectional view of the dispenser in its normal position;

Fig. 2 is a similar view with the parts in the position which they occupy when the material is being dispensed through the delivery spout;

Fig. 3 is a transverse sectional view substantially along the line 3—3 of Fig. 1; and

Fig. 4 is a transverse sectional view substantially along the line 4—4 of Fig. 1.

Referring now to the drawings, 10 represents a receptacle in the form of a bottle which may be a conventional catsup bottle but preferably is molded so as to have an artistic shape and design suitable for a table ornament. It may be molded from glass, regular ceramic material, or any of the plastics provided such material is inert to the slightly acid condition of the material being dispensed. Generally the material being dispensed is catsup but of course the invention is not confined to the dispensing of that particular material.

The top of the receptacle is provided with a cap 11 which may be fitted and secured to the receptacle in any suitable manner but in this

instance has a threaded connection with the neck of the bottle, the neck being externally threaded and the cap having an internally threaded sleeve-like portion 12 which is screwed onto the threaded neck of the receptacle. Preferably the cap and the part formed integral with and extending into the receptacle are molded from a suitable plastic inert to the material being dispensed. The cap 11 has at one side an upward extension 13 forming in effect a delivery spout with a delivery opening 14 which in this instance is curved with its lower end in an off-center position somewhat adjacent to the neck of the bottle and its outer end at the side of the extension 13. It has been found that, with a delivery spout formed as shown, very little if any of the material tends to run down the outside of the spout and cap when the receptacle is placed in upright position after a dispensing operation.

In this instance, the part which supports and guides the ejecting mechanism is formed integral with the cap 11, this part, which is designated as a whole by the reference character 15, extending from the lower side of the cap down well toward the bottom of the receptacle. However, we do not regard it essential that the parts 11 and 15 be integrally formed. Molded in the cap 11 and extending down a suitable distance 30 in the extension 15 is a cylindrical well 16 which receives a coil spring 17 the lower end of which seats against a shoulder 18 at the bottom of the well and the upper end against a plunger 19 which slidably engages the upper part of 35 the wall of the well 16 and projects above the cap 11. This plunger 19 which forms a part of the ejecting mechanism is the only part which is located outside of the receptacle, and in this respect our device is far more desirable and 40 satisfactory than that shown in the Karcher patent wherein a substantial part of the operating mechanism is on top of the cap.

Secured to the lower part of the plunger 19 is an operating wire 20 which extends downwardly centrally of the coil spring 17 through the well 16 and then through an opening 21 which extends from the bottom of the well 16 to near the lower end of the extension 15. Where the wire 20 emerges from the opening 21 a suitable 45 wiper 22 may be provided to prevent the entrance of catsup or other material into the opening 21 and well 16. The lower end of the wire 20 where it extends beyond the opening 21 is in this instance curved laterally and is connected to one 50 end of a combined lever and agitator 23, the latter having a spoon-like body portion 24 and an arm 25 which extends through a slot in the lower end of the extension 15 and is pivoted intermediate its ends at 26 to the two side walls 55 27 of the slot, the lower end of the wire 20 be-

ing pivotally connected to the free end of the arm 25. Any suitable means may be provided for limiting the movements of the member 23 and therefore of the plunger 19 and of the ejector to be referred to presently, but in this instance the wall 27a at the lower end of the slot serves as a shoulder or stop to limit the swinging movement of the arm 25 and therefore of the member 23 as a whole in both directions.

To the free end of the spoon portion 24 of the member 23 is pivotally connected the lower end of a wire 28 which extends upwardly between the extension 15 and the side of the bottle and which at its upper end is attached to an upwardly dished substantially circular ejector 29. A guide rib 30 is provided on the extension 15 to serve as a guide for the ejector 29, the latter having a slot 31 into which the guide rib 30 projects, as best shown in Fig. 3. The outer edge of the guide rib 30 conforms generally to the contour of that part of the receptacle which is opposite the guide rib, as clearly shown in Figs. 1 and 2, so that the ejector will be guided in its up and down movements by the inner wall of the receptacle and by the guide rib and is prevented from being accidentally disengaged from the latter.

The wire 21, the spring 17, the wire 28, and the part forming the pivot for the combined lever and agitator may be formed of stainless steel or other inert material. The lever and agitator 23 and the ejector 29 may be formed from inert plastic material, as, for example, that which is utilized in forming the cap 11 with its extension 15 and possibly also the receptacle 10.

Normally the parts occupy the relative positions shown in Fig. 1, but when it is desired to dispense material from the receptacle, the latter is tilted substantially as shown in Fig. 2 and then the plunger 19 is depressed causing the ejector to move toward the lower end of the delivery opening 14 and to discharge a predetermined quantity of the material from the outer end of the delivery opening, it being noted that the movement of the ejector 29 for its full stroke is toward the delivery opening. When the operator releases the plunger 19, the coil spring 17 immediately restores the plunger to its normal position shown in Fig. 1 and of course the user of the device may repeat the ejecting operation as many times as desired by repeatedly pressing down and releasing the plunger, and on the downward strokes of the plunger substantially the same measured or predetermined amounts of the material will be discharged through the spout, assuming that full strokes are given to the plunger 19. Smaller amounts can be dispensed by shortening the strokes of the plunger. When the device is righted or placed in its normal upright position shown in Fig. 1, it is found that very little if any of the dispensed material runs down the cap, this being due to the construction of the cap including the spout 13 and the disposition of the delivery opening 14 and especially the position of the outer end thereof.

By widening or giving the body portion of the part 23 a spoon shape, the latter serves to agitate the material in the receptacle so as to maintain it in the desired viscous condition suitable for ejection from the receptacle.

It will be seen from the above description that

the various objects enumerated in the early part of the specification are attained very effectively by the embodiment of the invention herein illustrated, but as changes may be made in the details of construction, including the relationship between the extension 15 and the cap 11 and the materials used in forming these and other parts, we aim in our claims to cover all modifications which do not involve a departure from the spirit 10 and the scope of the invention.

Having thus described our invention, we claim:

1. In a dispensing device of the character described, a receptacle having a cap with a delivery opening, an ejector movable toward and from the opening, and mechanism operable from the top of the cap for shifting said ejector, said mechanism including a lever operatively connected to the ejector and a single manually operable member connected to said lever and extending upwardly through the cap and accessible beyond the top thereof, the upper end of said member being shaped to be manually engaged and depressed to move the ejector toward the delivery opening, and a spring located beneath the top of the cap for shifting said member in one direction.

2. A dispensing device including a receptacle having a cap with a discharge opening, an ejector in the receptacle movable toward and from the opening, a lever operatively connected to the ejector, a member extending into the receptacle and constituting a support for said lever, and a plunger extending through the cap and adapted to be depressed to cause movement of the ejector toward said delivery opening, said member and said ejector having engaging means to guide the ejector for the full stroke of the latter.

3. A dispensing device including a receptacle having a cap with a discharge opening, an ejector in the receptacle movable toward and from the opening, mechanism for actuating the ejector including a part accessible at the top of the cap, a lever connected to the ejector and to said part, and a member extending from the cap into the receptacle and constituting a support for the lever, said member having a rib extending lengthwise thereof and constituting a guide for the ejector, the free edge of said rib having a contour corresponding substantially to the contour of the adjacent part of the receptacle.

4. A dispensing device of the character described including a receptacle having a cap with a delivery opening, an ejector movable toward and from the opening, a member depending from the cap and extending a distance into the receptacle, and mechanism for operating the ejector including a lever connected to the lower end of said member, and a rod connected to said lever and extending through said member and through the cap, said member having a guide rib projecting therefrom for the ejector and a spring housed in said member and adapted to be compressed when said rod is actuated, said spring surrounding the rod and being arranged between a lower shoulder of said member and an upper shoulder of said rod.
